UNITED STATES PATENT OFFICE.

THEODORE H. PROSKE, OF DENVER, COLORADO.

SHARPENING-MACHINE FOR DRILL-BITS.

No. 807,128.

Specification of Letters Patent.

Patented Dec. 12, 1905.

Application filed January 24, 1905. Serial No. 242,517.

To all whom it may concern:

Be it known that I, THEODORE H. PROSKE, a citizen of the United States, and a resident of Denver, in the county of Denver and State 5 of Colorado, have invented a new and Improved Sharpening-Machine for Drill-Bits, of which the following is a full, clear, and exact description.

The invention relates to sharpening-machines for drill-bits, such as shown and described in the Letters Patent of the United States No. 692,796, granted to me February 4, 1902.

The object of the present invention is to provide a new and improved sharpening-machine for drill-bits arranged to permit of sharpening various sizes of drills in a single pair of dies by the use of different-sized dollies, the sharpened drills being accurate and regular both in 20 gage and form to insure the drilling of straight holes without danger of the drill sticking in the hole.

The invention consists of novel features and parts and combinations of the same, as will be 25 more fully described hereinafter and then pointed out in the claim.

A practical embodiment of the invention is represented in the accompanying drawings, forming a part of this specification, in which 30 similar characters of reference indicate corresponding parts in all the views.

Figure 1 is a side elevation of the improvement, parts being broken out. Figs. 2, 3, and 4 are enlarged side elevations of a set of dollies to be used in the machine. Fig. 5 is an enlarged face view of the sectional die in position in the guideways of the machine. Fig. 6 is a plan view of the lower die. Fig. 7 is an inverted plan view of the upper die. Fig. 35 8 is a longitudinal sectional elevation of the lower die, the section being on the line 8 8 of Fig. 6. Fig. 9 is a similar view of the same on the line 9 9 of Fig. 6, and Fig. 10 is a side elevation of the drill-bit.

On a suitably-constructed bed or frame A is held a vertically-disposed guideway B, in which fit dies C and C' in the form of blocks and of which the lower or anvil die C is removably held on a suitable support D, extending 45 between the sides of the guideway B, as plainly indicated in Fig. 5. The upper or hammer die C' is removably held on a cross-head E, mounted to slide vertically in the guideway B and connected with the piston-rod 50 F' of a pneumatic or other hammer F of any approved construction and employed for im-

parting a reciprocating motion to the hammer-die C' or to hold the latter in a closed position on top of the anvil-die C during the time the cutting edges of the drill-bits are sharpened, 60 as hereinafter more fully described.

The dies C and C' are provided in their opposite faces with longitudinally-extending registering recesses C² C³ and C'² C'³ for receiving and carrying the bit of the drill G, 65 the rear end of the shank of which is adapted to rest on an abutment-block H, mounted to slide longitudinally on the bed A. The abutment-block H is provided with a fixed-nut H', in which screws a screw-rod I, extending longitudinally and journaled in suitable bearings carried by the bed A. The forward end of the screw-rod I is connected by a gearing I' with a transverse shaft I², journaled in the bed A and carrying at its outer 75 end a crank-arm I³ under the control of the operator for turning the shaft I² to rotate the screw-rod I with a view to moving the abutment-block H forward or backward, according to the length of the shank of the tool under treatment at the time.

The registering recesses C² C³ are each V-shaped in cross-section and taper from the front ends of the dies C C' to the rear ends thereof, as plainly indicated in Figs. 6 and 7, 85 the object being to allow sharpening different-sized drill-bits in the same die-blocks—that is, a large-sized bit fits the recesses C² C³, at or near to the front end thereof, while smaller-sized bits fit farther to the rear in the 90 recesses.

The bits are acted on while in position in the registering recesses C² C³ by dollies having their heads of different tapers to allow the heads to enter the forward ends of the recesses C² C³, according to the size of the drill-bit in position at the time in the recesses C² C³ of the dies C C'. Thus for a large-sized drill held in the forward end of the recesses C² C³ a dolly J is used, such as shown in Fig. 2, the head 100 J' of which fits the forward end of the said recesses. When a tool with a medium-sized drill-bit is held in the registering recesses C² C³ of the dies C C', then a dolly J², having a head J³, such as shown in Fig. 3, is used, 105 as this head so tapers as to fit into the forward end of the registering recesses to act on the bit in position in the dies at the time. In a like manner a small-sized bit is acted on by a dolly J⁴, having a tapering head J⁵, such as 110 shown in Fig. 4 and somewhat longer than the head shown in the dolly represented in

Fig. 3 to allow this dolly to enter the registering recesses $C^2 C^3$ a considerable distance in order to strike the cutting edges of the small-sized bit in position in the dies $C C'$ at 5 the time.

Each of the dollies is adapted to be connected with the piston-rod K' of a pneumatic or other hammer K , mounted on a support L , held on the bed A , the said support L being 10 also provided with a bearing L' for the dolly J to slide in.

The registering recesses $C^4 C^5$ in the dies $C C'$ are for cross-forming purposes, and when a drill-bit is in position in the lower recess 15 C^4 and the upper die C' is caused to reciprocate by the action of the hammer F then the drill-bit is cross-formed in the usual manner, it being understood that the recesses $C^4 C^5$ have tapering bottoms, as indicated in Fig. 8, 20 to allow of cross-forming different-sized drill-bits. The lower die C is provided at its forward end with a stop C^6 , extending transversely across the forward end of the recess C^4 to limit the movement of the drill-bit when 25 inserted in the lower recess C^4 at the time the upper die C' is in raised position.

It is understood that when the drill-bit is in the cross-forming recesses $C^4 C^5$ the upper die C' is reciprocated; but when the drill-bit 30 is in position in the registering recesses $C^2 C^3$ then the upper die C' is held in a lowermost position—that is, on top of the anvil-die C —during the time the corresponding dolly is active—that is, reciprocated from the hammer K —to sharpen the cutting edges of the drill-bit.

It is understood that the width of the drill is reduced the farther back it is held while being hammered in the recesses $C^4 C^5$, and it 35 will be noted that these recesses $C^4 C^5$ correspond in taper with the recesses $C^2 C^3$ for upsetting the drill in, and by drawing the drill back the end of the drill is hammered down to the required width before it is placed into 45 the upsetting recesses $C^2 C^3$.

Suitable means are employed to enable the operator in charge to stop and start the hammers F and K , according to the nature of the

work under treatment at the time; but as such means are of ordinary construction it is 50 not deemed necessary to further illustrate or describe the same.

It is understood that by the use of the machine the drills are side-set and cross-formed while held in the recesses $C^4 C^5$ and while the hammer-die is reciprocated, the latter forging the cross-form and at the same time forming the bevel or cutting edge on the face of the drill and the taper or clearance. After this operation the drill is upset or its cutting edges 60 sharpened—that is, the drill is placed into the recesses $C^2 C^3$ with the hammer-die C' held in a closed position and the corresponding dolly reciprocating by the action of the hammer K to upset the forward or cutting end of the 65 drill-bit. Drills sharpened by this machine are regular in gage and form and capable of drilling straight holes without danger of the drills sticking in the holes.

Having thus described my invention, I claim 70 as new and desire to secure by Letters Patent—

A sharpening-machine for drill-bits, provided with a pair of dies, each having a V -shaped recess in its working face, the recesses registering with each other and tapering from 75 the front ends of the dies to the rear ends thereof, whereby provision is made for holding different-sized drill-bits in the same recesses of the dies with their ends at varying distances from the front ends of the dies according to size, and a dolly having a tapering 80 head for entering the recesses of the dies to upset or sharpen the bits, the taper of the head of the dolly corresponding to the taper of the recesses and the head being of a length 85 to enter the recesses of the dies a distance equal to the distance the bit is held within the said recesses according to the size of bit.

In testimony whereof I have signed my name to this specification in the presence of two sub- 90 scribing witnesses.

THEODORE H. PROSKE.
